UNITED STATES PATENT OFFICE.

ALBERT H. DICKINSON, OF KANSAS CITY, MISSOURI.

GAME APPARATUS.

Application filed January 6, 1922. Serial No. 527,368.

To all whom it may concern:

Be it known that I, ALBERT H. DICKINSON, a citizen of the United States, residing at Kansas City, in the county of Jackson and State of Missouri, have invented certain new and useful Improvements in Game Apparatus; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to a game apparatus and more particularly to one whereby the various plays of a baseball game may be indicated by means of a spinning top upon a field representative of an ordinary baseball field, the object of the invention being to reproduce the plays made by opposing teams by means of an object representative of a ball in play and obstacles whereby the travel of the ball is arrested at various points throughout the field.

In accomplishing this object I have provided improved details of structure, the preferred form of which is illustrated in the accompanying drawings, wherein—

Fig. 1 is a perspective view of the apparatus including the playing field and ball member, a part of the confining wall being broken away to illustrate a feature of the field board.

Fig. 2 is a detail perspective view of a peg holder and pegs comprising a part of the apparatus.

Fig. 3 is a detail perspective view of a scoring device also employed with the apparatus.

Referring more in detail to the drawings:

1 designates the playing field, which may be constructed of a heavy sheet of cardboard, preferably squared and confined within a box-like enclosure 2, forming the four sides of the field. The board 1 at one corner is marked to form the base paths 3 and the four base positions, 4, 5, 6 and 7, corresponding to the home plate, first, second and third bases respectively. The paths, the bases and the territory surrounding the paths is indicated by printing the same on the board in colors different from that of the in and out fields, the fields being preferably printed in a green color to resemble the usual playing field, the territory adjacent the

paths being yellow to correspond to the color of soil, and the paths themselves being preferably white to distinguish them from the field and in-field playing territory.

At each of the base positions is a socket 5', 6', 7', adapted for receiving pegs 8 indicating players occupying the various base positions, the home plate being smooth in order to avoid any interference with the movement of the playing object at that point.

The field sheet 1 is scored diagonally at the corner upon which the diamond appears and is raised to form an incline from the home plate in the direction of the playing field, the raised corner of the plate being supported on a block 9 and held permanently in position as indicated in Fig. 1.

The object or ball member comprises a handle member 10 which extends into a spherical body or ball 11, and a spindle point 12, which extends from the body diametrically opposite the handle member, the spindle being of only sufficient length to permit the top to spin freely without interfering with the seating of the ball member 11 in the various sockets located throughout the field adapted to receive and hold the ball to indicate a play, as will presently be described.

The ball-receiving sockets 13 are located at various points and in close proximity throughout the playing field and are of substantially less diameter than the ball member so that the latter may come to rest therein when the spinning force of the top has been expended, the thickness of the board being such that the ball member will set peripherally in the sockets without projecting therethrough, and being greater than the length of the spindle so that the latter may project into the socket when the ball is set without contacting the bottom of the box-like container of which the walls 2 form the side members.

Surrounding the sockets are rings 13' and printed on the rings are indications of the various plays in the game, such as outs, one, two and three base hits, home runs, errors, bunts, sacrifice hits or any other indication that may be desirable or customary in an ordinary game of baseball.

The first and third base lines are extended to form the usual foul lines, and the sockets 13 are located outside of the base lines so that should the object member come to rest

in one of the outside sockets, the play of a foul ball may be indicated by the printing on the ring surrounding the sockets. Plays on the foul territory sockets are, of course, limited to outs and errors although foul strikes may be recorded on the scoring device should the object member fail to set in one of the sockets.

- Located within the diamond and spaced 10 transversely thereacross at about the pitcher's position are pins 14, forming a barrier against which the object ball may contact to check the travel after it leaves the incline, and located inside of the barrier 15 are sockets 15 of slightly greater diameter than the out-field sockets, the in-field sockets being located in such proximity that narrow paths are formed therebetween, over which the spindle must pass to reach the barrier 20 and pass therethrough to the outer field, thereby increasing the probability of the ball stopping within the in-field and thereby providing a close approximation to the play in an actual baseball game wherein 25 the greatest number of outs are made in the in-field. The in-field sockets are marked to indicate strikes and balls as all of the players' positions are assumed to be at that part of the field back of the barrier.
- 30 In addition to the ball and strike indications adjacent the in-field sockets are other indications of plays which may occur with men on bases, such for instance, as the stealing of a base by a player who is occupying 35 one of the base positions when a strike is made.

The game may be played by two persons representing opposing teams, one of whom may spin the top from the home position 40 so that it will pass down the incline and come to rest in one of the sockets in either the in-field or the out-field, the barrier pins reverting the travel of the object ball which may follow an irregular course to various 45 points in the field because of its being diverted by a barrier or by the temporary location of the ball in one of the receiving sockets. When the ball has finally come to 50 rest in one of the sockets, the play indicated on the surrounding ring is entered on the scoring device and the play resumed until the first player has made three outs, the intermediate playing being progressively indicated on the field by means of the pegs 55 which will be inserted into the various base

sockets and progressively advanced according to the instructions on the socket rings, or removed when the play indicates that a man on base has been put out.

When the first player has completed his 60 part of the inning, the second player takes the ball and continues the play with it until he in turn is retired. The first player then proceeds with his second inning and the game is continued for any selected number 65 of innings, the player having made the most runs at the end of the game being declared the winner as in an ordinary game of baseball.

Having thus described my invention, what 70 I claim and desire to secure by Letters-Patent is:

1. A game apparatus comprising a playing field having sockets therein and having an inclined portion, a barrier extending 75 across the field at the foot of the inclined portion and comprising spaced pins, and a top adapted for spinning on the field for travel between the pins and for location in any of the said sockets, the sockets at the 80 side of the barrier adjacent the incline being of greater diameter than those at the opposite side of the barrier, for the purpose set forth.

2. A game apparatus comprising a board 85 representative of a baseball diamond and provided with sockets, pins forming a barrier across the diamond between the home and second base positions, and a spindle comprising a spherical body adapted for 90 passage between the barrier pins and for seating in said sockets, the board being inclined from home base position to a point between said position and the barrier.

3. A game apparatus comprising a board 95 representative of a baseball diamond and provided with sockets, pins forming a barrier across the diamond between the home and second base positions, and a spindle comprising a spherical body adapted for 100 passage between the barrier pins and for seating in said sockets, the board being inclined from home base position to a point between said position and the barrier, the sockets in that part of the board at the home 105 base side of the barrier being of greater diameter than those at the opposite side of the barrier, for the purpose set forth.

In testimony whereof I affix my signature.
ALBERT H. DICKINSON.
